UNITED STATES PATENT OFFICE.

HENRY HAFKER, OF HOBOKEN, NEW JERSEY.

CLOTHES-LINE HOLDER.

SPECIFICATION forming part of Letters Patent No. 672,763, dated April 23, 1901.

Application filed January 29, 1901. Serial No. 45,187. (No model.)

To all whom it may concern:

Be it known that I, HENRY HAFKER, a citizen of the United States, and a resident of Hoboken, in the county of Hudson and State of New Jersey, have invented a new and Improved Clothes-Line Holder, of which the following is a full, clear, and exact description.

The purpose of the invention is to provide a device adapted to connect the ends of a pulley-line in an adjustable manner and so that the line may be quickly slackened or its ends disconnected and as conveniently and expeditiously stretched and the ends of the line connected and safely held in adjusted position.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the connecting block or medium between the ends of a pulley-line, parts of the line being also shown, the line where it passes through the connecting block or medium being in position for slackening or tightening. Fig. 2 is a view similar to Fig. 1, the free end of the line being shown locked in the connecting block or medium; and Fig. 3 is a horizontal section through the block or connecting medium for the ends of the line.

A represents a connecting-block for the ends B and B' of a pulley-line C. The end B' of the pulley-line is attached to one end of the block A, preferably through the medium of an extension 10 at one end, having an aperture 11 formed therein. The opposing end of the pulley-line is passed through an aperture 12, horizontally produced in the opposite end of the block or connecting medium A, and into a central chamber 13, in which chamber

a drum 14 is mounted to revolve, the said drum being provided with trunnions 14^a, held to turn loosely in the side portions of said block. The drum 14 is provided with a spiral groove 15, which groove decreases in depth in direction of one of its ends, and in the faces of the chamber 13, which are opposite the peripheral portion of the drum 14,

grooves 16 are produced, which receive the coils of the cord or line when the line is wound upon the said drum. In addition to these 55 regular grooves 16 another groove 17 is produced in one face of the chamber 13, and the groove 17 coincides with the groove 15 on the drum. The said groove 17 decreases in depth as it approaches the upper face of the block 60 or connecting medium A. The special groove 17 may and usually does connect at its lower portion with an adjacent regular groove 16.

When the line has been coiled around the drum, its coils enter the grooves or recesses 65 16 in the wall of the chamber 13 of the connecting-block A, and as long as the free end of the line B is kept out from the spiral groove 15 in the drum the line may be slackened or tightened, as desired. When the proper adjustment of the line has been attained, the free end of the line is carried over into the spiral groove 15 of the drum and the coinciding or corresponding recess in the wall of the chamber 13 of the connecting-block, and when 70 75 pressure is brought to bear on the pulley-line the drum will be turned to such an extent and in such a direction that the free end of the line will be clamped between the reduced portion of the spiral groove 15 in the drum 80 and the reduced portion of the recess or groove 17 in the block. The free end of the line will thus be held firmly locked to the block. When another adjustment is to be made, it is simply necessary to carry the free end of the 85 line from out of the groove and recess 15 and 17 over upon the plain surface of the drum, the coils of the line on the drum at that time being in the recesses or grooves 16 only, and at this time the drum is free to turn until the 90 line has been lengthened or shortened, as occasion may demand.

Having thus described my invention, I claim as new and desire to secure by Letters Patent—

1: A clothes-line holder comprising a connecting-block adapted to unite the ends of the clothes-line, said block being provided with a central chamber and a drum mounted to revolve in said chamber, the said drum being 100 provided with a peripheral spiral groove decreasing in depth in direction of one end, a wall of the said chamber being provided with a coinciding groove also decreasing in depth

in direction of one end, the opposite walls of said chamber being further provided with grooves adapted to receive a portion of the coils of the line when the line is wound upon 5 the drum, as specified.

2. In a clothes-line holder, a connecting-block provided with a central chamber, means at one end for attachment to an end of the pulley-line, the opposite end of the said block 10 having an opening therein leading into the said chamber adapted to receive another end of the pulley-line, a drum mounted to turn in the said chamber, the said drum being provided with a peripheral spiral groove diminishing in depth in direction of one of its ends, 15

a wall of the said chamber of the block having a coinciding groove diminishing in depth in direction of the upper face of the block, opposing walls of the said chamber being further provided with recesses or grooves adapted to receive portions of the coils of the line when the line is wound upon the said drum, for the purpose described. 20

In testimony whereof I have signed my name to this specification in the presence of 25 two subscribing witnesses.

HENRY HAFKER.
